FRUIT TRAY

Hugh R. Weiss, 164 S. Mountain Ave., Montclair, N.J.

Filed Dec. 1, 1961, Ser. No. 67,765

Term of patent 14 years

(Cl. D58—13)

Fig. 1

Fig. 2

Fig. 3

I claim:

The ornamental design for a fruit tray, as shown.
